LOCK

Sophie S. Karavia, New York, N. Y.

Application May 8, 1940, Serial No. 333,901

3 Claims. (Cl. 79—146)

My invention relates to locks and has particular reference to locks of a self-closing type, such as are used for doors, safes, etc.

In ordinary door locks a bolt is usually employed having a tapered end so that it can be pushed out of the way in closing a door, a spring being provided to push the bolt back into a locking position when the bolt registers with a corresponding hole in a door frame. In order to make the lock safe against being picked or opened by a thin tool inserted into a crack between the door and the frame, a second bolt usually is provided, which is moved in its place by a key-operated locking mechanism. The necessity of using a key for locking the door deprives the lock of an advantage of being fully automatic.

In order to overcome this disadvantage, I have provided a lock which is entirely automatic in its locking action, so that both bolts are moved into the locking position by closing the door. For unlocking the door, both bolts are simultaneously moved either by a key from the outside or by a handle from the inside. In order to make my lock safe against being picked, I provide two bolts which are moved in the opposite directions, the tapered bolt moving the door portion of my lock while the second bolt moves in a frame or stationary portion of the lock.

My invention is more fully described in the accompanying specification and drawing in which:

Fig. 1 is a sectional view of a frame portion of my lock;

Fig. 2 is a sectional view of a door portion of my lock;

Fig. 3 is a front view of the frame portion;

Fig. 4 is a sectional view taken on the line 4—4 of Fig. 1;

Fig. 5 is a sectional side view of both lock portions in the locking position;

Fig. 6 is a sectional view of the door portion in an unlocked position;

Fig. 7 is a sectional side view of the door portion;

Fig. 8 is a detail view of an operating arm;

Fig. 9 is a top view of the door portion.

My lock is shown in the accompanying drawing in one of its forms adapted for use in connection with doors. It comprises two portions, one portion being fitted into a corresponding recess in a door, the other portion being fitted in a recess in a door frame. The first portion will be therefore, for convenience, called "door portion," the other being "frame portion." It is

understood, of course, that the same portions may be used in connection with other structural parts or elements which it is desired to provide with locks.

5 The door portion consists of a casing 1 having a front plate 2. The casing is divided into compartments 3 and 4 by a wall 5, the plate 2 having corresponding openings 6 and 7. The lower compartment has a bolt 8 having a beveled end 9 so placed that the bolt is pushed back when the door is being closed. A plunger 10 is slidably fitted in the second compartment or pocket 3 and has a rod 11 passing through a hole in a wall 12 with a knob 13 at the end. A spring 14 tends to keep the plunger in the withdrawn or inward position. A lever 15 is pivoted at 16 on the wall 5, one end of the lever engaging the rod 11 between pins 17, the other end having a slot engaging a pin 18 on a reduced portion 19 of the bolt 8. The lever 15 is so positioned that the bolt 8 is fully withdrawn when the plunger 10 is moved into an operative position with its front end flush with the surface of the front plate 2. The plunger can be moved by curved 20 25 forked arms 20, 20' engaging the knob 13, the arms being mounted on shafts 21, 21', passing through the walls of the casing 1.

The shaft 21' has at the end a slot 22', Fig. 7, for a lock mechanism 23 operated by a key 24, the shaft 21 having a slot 22 for a handle 26. Each shaft therefore can independently move the plunger through its arm.

Opposite the casing 1 a second casing 27 is fitted in a door frame, its front plate 28 being provided with holes 29 for screws. The casing is divided by a wall 30 into two compartments or pockets 31, 31', the plate 28 having corresponding openings 32 and 33. A bolt 34 is slidably fitted in the upper compartment 31' opposite the opening 6 in the plate 2. The bolt has a longitudinal hole 34' for the end of a guiding rod 35. The other end of the rod is held in a block 36 attached to the rear wall of the casing 27. A spring 37 urges the bolt outward. The bolt is retained in an inoperative position by a pin 38 engaging a corresponding hole 38' in its side. The pin extends from a lever 39 rotatively mounted on a shaft 40 held in brackets 41 attached to the wall 30. The latter has a slot 42 for the pin 38. A coil spring 43 is placed on the shaft 40, pressing the lever against the wall 30 and holding the pin 38 in the hole 38'. The lever 39 has an arm 44 extending at an angle to the wall 30 as shown in Fig. 1, so that it can be engaged by the beveled end 9 of the first bolt

8. The lever, when engaged by the tapering end 9, turns outward against the pressure of the spring 43, withdrawing the pin 38 from the hole 38' and thereby releasing the second bolt. The latter moves under action of the spring 37, entering the opening 6 in the plate 2 of the first casing. A pin 45 at the side of the bolt 34 engages the inner side of the plate 28, thereby limiting the outward movement of the bolt.

It follows, therefore, that the door, when fully closed, is automatically locked by the first bolt 8 entering the opening 32 in the front plate of the second casing and, at the same time, the bolt 8 releases the second bolt 34 which also automatically locks the door by entering the opening 6 in the front plate of the first casing.

For opening the door, the shaft 21 is turned, either by a key 24 from the outside or by the handle 26 from the inside. The arm 20, pressing on the knob 13, moves the plunger 10 outward, thereby forcing the second bolt 34 back into its compartment 33. An inclined slot 46 is provided in the second bolt 34, the cam-shaped bottom side of the slot raising the pin 38 until it reaches the hole 38' and drops into it, locking the second bolt in the withdrawn or inoperative position. The outward movement of the plunger 10 at the same time causes withdrawal of the first bolt 8 from the second casing through the lever 15. Both bolts, being now withdrawn, as shown in Fig. 6, the door is unlocked and can be opened.

For locking the first plunger in a withdrawn or inoperative position, it is provided with a hole 47 at the end which can be engaged by a latch 48 slidably fitted in the plate 2. The latch can be manually moved upward when the plunger is in its outward or operative position, as shown in Fig. 6, thereby locking the plunger in this position.

My lock is also provided with an additional safety feature for preventing it being opened from the inside if the door was locked from the outside. Thus, a burglar may be prevented from opening the door from the inside if he had gained entrance through a window, for instance. The lock, for this purpose, is provided with a locking bar 50 slidably mounted in a slot in the wall 12 and having a pointed end adapted to engage a notch 51 in the shaft 21.

The bar 50 is connected by a screw 52 with a rod 53 slidably supported on top of the casing 1 and enclosed by an added casing extension 54. The end 55 of the rod 53 passes through a hole in the front plate 2 and can be pushed by a suitable instrument, or, if the rod is made of a larger diameter, by a finger, thereby moving the bar 50, for locking the shaft 21 against rotation by the handle 26. A second rod 56 is placed alongside the rod 53 and has an end 57 extending through the plate 2, the two rods being pivotally connected together by a lever 58 at 59, 60, the latter being pivoted at 61 to a bracket 62 mounted on the upper wall of the casing 1. The ends of the rods 53 and 56 slide in corresponding holes in the bracket 62. By pushing inward the end 57 of the second rod, the first rod 53 is retrieved, thereby returning the bar 50 into its inoperative position. It is possible, therefore, by operating one or the other rod, to lock or to unlock the shaft 21.

The locking mechanism 23 is preferably attached to the casing 1 by two screws (not shown) passing from the inside through a portion of the door at the handle, through the holes 72 in the walls of the casing 1, through another portion of

the door at the locking mechanism 23, and finally into tapped holes in the locking mechanism or cylinder 23.

In certain cases it is desirable to provide means to prevent the operation of the locking mechanism, as, for instance, if there is a danger that someone may open the door at night with a duplicate key. I provide for this purpose a locking lever 63 pivoted at 64 on the wall 5 and having a curved pointed end 65. The lever is normally held with its point beyond the end of the arm 20'. If the lever 63 is turned, however, its point 65 will be placed in front of the arm 20', preventing the latter from moving when attempt is made to turn the shaft 21 by the key 24.

For turning the lever 63 it is provided with an extension rod 66, whose outer end passes through a hole in the casing 1 and is engaged by a sliding rod 67. The latter has a cylindrical end of a reduced diameter at the front, sliding in a corresponding hole in the front plate 2. The other end of the rod 67 is also of a reduced diameter and slides in a bracket 68. The front end of the rod 66 can be depressed by a suitable instrument, or, if it is made of a sufficiently large size, by a finger, for moving the rod 67 and turning the lever 63 into a position for locking the arm 20' against being turned by the key 24. For unlocking the lever 63 a second rod 69 is mounted alongside the rod 67 with its end extending through the front plate 2. The two rods are connected by a lever 70 similar in all respects to the lever 58 and pivotally supported at 71 on the bracket 68. By pushing the second rod 69 inward, the first is moved outward by the lever 70, thereby returning the lever 63 into an inoperative position. The casing 1 has an extension 72' over the rods 63 and 67.

It is understood that my lock may be further modified without departing from the spirit of my invention, within the scope of the appended claims.

I claim as my invention:

1. A lock for locking together two relatively movable members comprising a first casing adapted to be fitted in the first member, a second casing adapted to be fitted in the second member, the outer portion of the first casing being adapted to register with the outer portion of the second casing when the two members are brought together, a bolt slidably fitted in the first casing and having a beveled end portion, a yieldable resilient means for moving the beveled bolt outward, the bolt being adapted to be moved inward by the pressure of the second casing when the two members are moved together, the second casing having a pocket for receiving the beveled end of the first bolt, the latter being thereby adapted to lock the two casings together when the pocket registers with the first bolt, a second bolt slidably fitted in the second casing, a yieldable resilient means for moving the second bolt outward, the first casing having a pocket for the second bolt, means to retain the second bolt inside the second casing against the action of its resilient means, means to release the second bolt by the end of the first bolt entering its pocket in the second casing, thereby permitting the second bolt to enter its pocket in the first casing for locking together the casings by both bolts, means to manually retract both bolts, thereby releasing the two members with the casings for relative movement apart, a plunger movably supported in the first casing adapted to abut the end of the second bolt when

the latter is moved into its pocket in the first casing, and a manually movable member at the first casing for retaining the plunger in the outward position with the first bolt withdrawn into inoperative position.

2. A lock for locking together two relatively movable members comprising a first casing adapted to be fitted in the first member, a second casing adapted to be fitted in the second member, the outer portion of the first casing being adapted to register with the outer portion of the second casing when the two members are brought together, a bolt slidably fitted in the first casing and having a beveled end portion, a yieldable resilient means for moving the beveled bolt outward, the bolt being adapted to be moved inward by the pressure of the second casing when the two members are moved together, the second casing having a pocket for receiving the beveled end of the first bolt, the latter being thereby adapted to lock the two casings together, when the pocket registers with the first bolt, a second bolt slidably fitted in the second casing, a yieldable resilient means for moving the second bolt outward, the first casing having a pocket for the second bolt, a plunger movably supported in the first casing adapted to abut the end of the second bolt when the latter is moved into its pocket in the first casing, a shaft passing through the side walls of the first casing and

30

formed of two portions mounted for rotation independently of each other, arms extending from the shaft portions independently operatively connected with the plunger, means to manually rotate one portion of the shaft from one side of the casing, means to manually rotate the other portion of the shaft from the other side of the casing for moving the plunger outward, thereby ejecting the second bolt from the first casing and disengaging the casings and a manually operable locking mechanism for one of said shaft portions.

3. A lock for locking together two relatively movable members, comprising a casing adapted to be fitted into one of the members, a bolt slidably fitted in the casing adapted to engage the other member, a plunger slidably supported in the casing, a lever rotatively supported at the middle in the casing, one end of the lever engaging the bolt, the other end of the lever engaging the plunger, two shafts rotatively and co-axially supported in the opposite sides of the casing extending to the outside of the member and adapted to be manually rotated, lever arms at the inner ends of the shafts engaging the inner end of the plunger and adapted to move the plunger, thereby moving the bolt, and means to render one of the levers inoperative.

SOPHIE S. KARAVIA.
